BRUSH FOR CLEANING PERFORATED CASING

Filed July 15, 1940

INVENTOR:
CLAIR J. GIBSON
By *Martin G. Quinn, Atty.*

UNITED STATES PATENT OFFICE

2,296,514

BRUSH FOR CLEANING PERFORATED
CASING

Clair J. Gibson, Los Angeles, Calif.

Application July 15, 1940, Serial No. 345,592

9 Claims. (Cl. 166—18)

My invention relates generally to brushes and more particularly to a brush that is designed for use in cleaning the perforations and slots in the perforated linings used in oil wells, for cleaning the inner surfaces of well casings and linings, and for cleaning mud and other accumulations from the surface of the formation through which the well hole passes.

My present invention is an improvement on the construction of the brush disclosed in my co-pending application for U. S. Letters Patent filed November 20, 1939, Serial No. 305,288.

The principal objects of my present invention are, to generally improve upon and simplify the construction of the brush disclosed in my aforesaid copending patent application, as well as other existing forms of similar brushes, further, to provide for mounting the bristles of the brush and which bristles are formed of wire, upon supporting bodies that are associated to form an elongated rigid body, to provide simple and efficient means for maintaining the separate bristle carrying bodies in assembled relation, to provide resilient means above and below the assembled bristle carrying bodies so as to center and guide the brush in its movements through the well casings and liners and further, to provide a simple form of wire bristle that is mounted on its supporting body so as to be highly effective in performing its intended functions, namely, the brushing and scraping of the inner surfaces of oil well liners and casings and to enter and pass through the perforations or slots in the liner so as to effectively remove therefrom accumulations of sand, scale, chemical deposits and the like, in order to permit oil to flow more freely from the well and the formation surrounding the same into the liner and casing.

Further objects of my invention are, to provide a brush of the character referred to that is of strong, substantial construction, capable of being readily assembled or taken apart, to construct the brush from a series of substantially identical bristle carrying members that may be assembled so as to form brushes of any desirable and workable lengths and further, to construct a brush that, if desired, may be utilized in connection with a conventional oil well packer.

With the foregoing and other objects in view, my invention consists in certain novel features of construction and arrangement of parts that will be hereinafter more fully described and claimed and illustrated in the accompanying drawing in which:

Fig. 1 is a vertical section taken through the center of a brush constructed in accordance with my invention.

Fig. 2 is an enlarged horizontal section taken on the line 2—2 of Fig. 1.

Fig. 3 is an enlarged horizontal section taken on the line 3—3 of Fig. 1.

Fig. 4 is an enlarged horizontal section taken on the line 4—4 of Fig. 1.

Fig. 5 is an enlarged horizontal section taken on the line 5—5 of Fig. 1.

Fig. 6 is an elevational view of a modified form of resilient guide utilized at the lower end of the brush.

Fig. 7 is an enlarged horizontal section taken on the line 7—7 of Fig. 6.

Fig. 8 is a detail section similar to Fig. 7 and showing a modified construction.

Fig. 9 is a perspective view of the cylindrical body that carries the wire bristles.

Fig. 10 is a plan view of one of the wire bristles.

Fig. 11 is an enlarged horizontal section taken on the line 11—11 of Fig. 1.

Fig. 12 is a sectional view similar to Fig. 11 and showing a modified form of the wire bristles.

Fig. 13 is a vertical section showing a conventional packer associated with the brush and said brush and packer positioned in a well hole.

Figs. 14, 15 and 16 are plan views of modified forms of the wire bristles used in the production of the brush.

Referring by numerals to the accompanying drawing which illustrates a preferred embodiment of my invention, 10 designates a rod which may be of any desired and convenient length and which serves as a carrier for the short cylindrical members or collars that carry the wire bristles of the brush and the upper end of this rod is screw seated in the lower portion of a coupling member 11.

Screw seated in the upper portion of the coupling 11 is the lower end of a rod 12 that carries the upper one of the resilient guides for the brush and mounted on the upper end of this rod 12 is a conventional swivel socket 13 provided at its upper end with a threaded pin 14 whereby the brush may be detachably connected to the lower end of a drill string or the tools carried thereby.

The means for centering and guiding the upper portion of the brush during its travel through the well hole or casing comprises a plurality of bow-shaped members 15 of resilient metal, the end portion of which occupy vertically disposed grooves 16 that are formed on the inner surface of a collar 17. This collar is arranged for sliding movement on rod 12 below the socket 13 and said collar is held against rotary movement on the rod by means of a key 18 that is seated in said rod and which occupies a slot in the collar.

The upper ends of the members 15 are bent outwardly as designated by 19 so as to overlie the upper edge of collar 17, and to secure said members 15 to the collar, pins 20 are seated in the collar and project into apertures that are

formed in those portions of the members 15 that occupy the grooves 16 (see Fig. 2).

The lower ends of members 15 are connected to a collar 21 that is identical with collar 17 and which is mounted for sliding movement on the lower portion of rod 12 and held against rotary movement on said rod by a key 22 that is identical with key 18.

To prevent accidental disconnection between the ends of the rods 10 and 12 with coupling 11, conventional set screws 23 are seated in coupling 11 and engage those portions of the rods that are screw seated in said coupling.

The resilient guiding members 15 are preferably formed from flat resilient metal straps and the intermediate outer portion thereof are adapted to engage with rubbing contact the inner surfaces of the well casing liners or the formation surrounding the well hole.

The lower end of rod 10 terminates in an axial stem 24, the diameter of which is somewhat smaller than said rod and that portion of the rod immediately above said stem is threaded as designated by 25 for the reception of the internally threaded upper portion of a short tubular member 26 and to look this member on the rod a set screw 27 is seated in the upper portion of the tubular member and clamps the threaded portion 25 of rod 10. The lower portion of tubular member 26 or that portion below the portion that engages the thread 25 encloses stem 24 and formed in this portion of the tubular member and communicating with the opening therethrough are vertically disposed grooves 28.

Occupying grooves 28 are the shanks 29 of the resilient guides that are carried by the lower end of the brush, said guides being preferably formed from heavy resilient wire and those portions of the wire below the straight shanks 29 are bent outwardly to form substantially circular portions 30 that are adapted to yieldingly engage the inner faces of the well liner or casing.

The upper ends of the straight portions 29 of these resilient guides are bent outwardly at right angles to form short horizontally disposed fingers 31 that project through horizontally disposed apertures 32 formed through the intermediate portion of the wall of tubular member 26 (see Figs. 1, 4, and 5).

The construction just described enables the upper portions of the resilient guiding members to be inserted in the lower portion of the tubular member 26 and when the latter is screwed onto the lower end of rod 10, the stem 24 occupies a position between the straight portions 29 of the guides, thereby firmly securing the same to the lower end of rod 10.

In order to increase the effective rubbing contact between the outer portions of the curved lower ends of the resilient guides, the outer portions of the circular members 30 may be provided with straight flat faces such as 30a or said portions may be made substantially V-shape in cross section as designated by 30b (Fig. 8) and thus, as the brush is moved vertically in a liner or casing the contacting faces of the members 30 will scrape and cut away any accumulations that may have formed on the inner face of the liner or casing.

Removably positioned on rod 10 and clamped thereon between collar 11 and tubular member 26 is a series of short tubular members 33 that carry the wire bristles of the brush. Depending from the under side of the body of each member 33 around the opening therein is a concentric

rib 34 and for the accommodation of these ribs when the members 33 are positioned on shaft 10, the upper end of each member 33 is provided around the opening through said body with a concentric groove 35.

Formed in the wall of the bristle carrying member 33 and extending from the top downwardly to a point near the lower end are vertically disposed slots 36, preferably spaced equal distances apart.

In Fig. 9 which illustrates one of the bristle carrying bodies, the same is shown as being provided with six slots 36, but this number may be increased or decreased as desired.

The preferred form of the wire bristles used in the brush is illustrated in Fig. 10, each bristle being formed from a single piece of resilient wire, such for instance as used in pianos, and the central portion of the section of wire forming each bristle is bent to form an open loop portion 37 from which project straight diverging bristle portions 38.

Where the bristles are formed for use in connection with bristle carrying bodies such as 33 and provided with six slots 36, the straight portions 38 of each bristle are disposed substantially sixty degrees apart.

The bristles are pre-formed so as to conform with the slot arrangement in the bodies 33 and also to conform with the diameter of rod 10. The bristles are assembled on the body so that the curved central portion 37 of each bristle fits snugly within the opening through body 33 and with the straight portions 38 projecting outwardly through the adjacent members of a pair of the slots 36. Thus the curved central portions 37 of the bristles are in superimposed relation and said bristles are arranged so that an equal number of the straight portions 38 project outwardly through each slot 36, thus providing a uniform or balanced arrangement of the effective portions of the bristles.

In Fig. 11 I have illustrated the outer ends of the straight portions of the bristles passing through the slots or openings of a conventional perforated liner and which effect is attained while the brush is in service.

In Fig. 12 I have illustrated a brush having hairpin-shaped bristles 39 and where such construction is employed, the slots that are formed in the bristle carrying bodies must necessarily be formed tangent to the surface of the opening through the body.

Figs. 14, 15, and 16 show further modified forms of the wire bristles and for the accommodation thereof, the slots in the bristle carrying bodies must be correspondingly arranged. In all cases the bristles are pre-formed and their curved central portions are shaped so as to fit the rod 10 that passes through the entire series of bristle carrying bodies.

When the tubular bodies 13 are packed with bristles and assembled on the rod 10, they are clamped thereon by the coupling 11 that is screw seated on the upper end of the rod and by the tubular member 26 that is screw seated on the lower end of the rod and thus, the entire brush body comprising the rod and bristle carrying members clamp thereof is in effect a one piece structure.

In the use of my improved brush, the same after being lowered into the well is reciprocated and when used for cleaning the slots or openings in perforated liners the outer end portions of the bristles will as the brush is reciprocated, enter,

pass through, and then withdraw from the slots or openings so as to effectively remove all accumulations from said slots and as the bristles move lengthwise within the lining they will flex first in one direction and then in the other so as to scrape and clean those portions of the inner face of the liner between the slots or openings therein.

In a similar manner the brush is reciprocated within casing so that the outer ends of the resilient straight portions 38 of the bristles will engage and brush all accumulations from the surface or surfaces with which the bristles contact.

Where my improved brush is used in connection with a packer, the latter is detachably connected to the lower end of the brush, after which the parts are lowered into the well, and said parts are now reciprocated so as to brush and clean the inner surface of the casing. The parts are now elevated until the packer is brought into position within the brushed and cleaned surface of the casing and after the packer has been expanded and set, the drill string is manipulated so as to detach the lower end of the brush from the upper end of the packer.

In some instances, my improved brush may be located on the lower part of a gas anchor and as the occasion demands, the combined parts reciprocated so that the brush will pass through and clean the perforations in the surrounding liner.

Thus it will be seen that I have provided a perforated casing clean brush that is relatively simple in construction, inexpensive of manufacture, and very effective in performing the functions for which it is intended.

It will be understood that minor changes in the size, form and construction of the various parts of my improved brush for cleaning perforated casing, may be made and substituted for those herein shown and described, without departing from the spirit of my invention, the scope of which is set forth in the appended claims.

I claim as my invention:

1. In a brush for cleaning perforated lining, casing, and the like, a rod, a series of tubular members mounted on said rod, said tubular members being provided with longitudinally disposed slots and wire bristles having portions encircling said rod and other portions that extend outwardly through the slots in said tubular members.

2. A brush for cleaning perforated lining, casing, and the like, as set forth in claim 1 and with means for clamping said tubular members on said rod.

3. A brush for cleaning perforated lining, casing, and the like, as set forth in claim 1 and with a resilient guiding and centering member on the lower portion of said rod.

4. A brush for cleaning perforated lining, casing, and the like, as set forth in claim 1 and with a resilient guiding and centering member on the upper portion of said rod.

5. In a brush for cleaning perforated lining, casing, and the like, a tubular member provided with a plurality of longitudinally disposed slots, a plurality of bristles formed of resilient wire and having curved portions positioned within said tubular member, with their end portions projecting outwardly through said slots, the curved central portions of which wires are staggered cir-

cumferentially so that the end portions of said wires that project through said slots are spaced apart longitudinally of the brush, thereby forming a plurality of longitudinally disposed rows of spaced bristles and a member extending lengthwise through said tubular member and through the curved portions of said bristles for maintaining said tubular member and bristles in assembled relation.

6. In a brush for cleaning perforated lining, casing, tubes, and the like, a core, a plurality of wire bristles, each having a curved central portion that partially encircles said core, those portions of the bristles beyond the curved central portion extending outwardly from the core, a tube surrounding said core and the curved central portions of said bristles, which tube is provided with longitudinally disposed slots through which the outwardly extending end portions of the bristles project to form longitudinally disposed single rows of bristles on the exterior of said tube and the curved central portions of said bristles being disposed with respect to each other so that the straight end portions of said bristles that project through the slots in said tube are spaced apart longitudinally of the brush.

7. In a brush for cleaning perforated lining, casing, and the like, a series of superimposed tubular members, each provided with a plurality of slots, a plurality of resilient wire bristles carried by each tubular member, the intermediate portion of each bristle being curved and arranged within one of said tubular members, with the end portions of each bristle projecting through certain of the slots in said tubular member to from single rows of bristles on the exterior of said tubes, the bristles in each row being spaced apart longitudinally of the brush and means passing through the entire series of tubular members and through the curved intermediate portions of said bristles for maintaining the same in assembled relation.

8. In a brush for cleaning perforated liners, casing, and the like, a core, a tube surrounding said core and provided with a plurality of longitudinally disposed slots, bristles having preformed intermediate portions of definite arcuate form which conform to the cross sectional shape of the core and substantially straight end portions that project in single rows through the slots in said tube and said bristles being arranged so that the straight end portions which project through the slots in the tube are spaced apart longitudinally of the brush.

9. In a brush for cleaning perforated liners, casing, and the like, a tubular member provided with a plurality of longitudinally disposed slots and a plurality of wire bristles mounted upon said tubular member and disposed in superimposed arrangement, each bristle having a curved intermediate portion that conforms to the inner periphery of the tubular member, each bristle having substantially straight end portions that project through the slots in the tubular member to form longitudinally disposed rows of single bristles, the curved intermediate portions of said bristles being disposed with respect to each other so that the straight projecting end portions thereof are spaced apart longitudinally of the brush and a member disposed axially within the tube and extending through the curved intermediate portions of said bristles.

CLAIR J. GIBSON.
